[57] ABSTRACT

This is a high speed non-electronic counter having a solenoid to trigger a spring driven counter mechanism. The counter mechanism comprises a numerated disc and a coil spring driven wafer having spring loaded detent pins each of which engage a stop mechanism to position the numbers on the disc. Actuation of the solenoid disengages the detent from the stop to permit the coil spring to rotate the wafer and disc until the next detent engages the stop mechanism thereby positioning the number corresponding to the position of the pin and stop.

HIGH SPEED ELECTRICAL COUNTER

BACKGROUND OF THE INVENTION

In a standard solenoid operated counter the power generated by the solenoid is used to operate the counter mechanism, and, since it is desirable to have counters operate as quickly as possible, numerous ways have been devised for increasing the speed of operation. For example, the solenoid return spring is made larger to move the counter quicker but this then requires a larger solenoid. Another scheme is to have the solenoid move a counter only part way upon energization and have the return spring move the counter the remaining part of the way when the solenoid is deenergized. Still another scheme is to employ various linkages which maximize the speed of response of the counter to the energization of the solenoid.

The invention disclosed herein differs from the foregoing prior art schemes since it does not rely on the power generated by the solenoid to operate the counter but utilizes the solenoid only to trigger the counter. This concept is carried out in this invention as described herein.

BRIEF DESCRIPTION OF THE INVENTION

In the embodiment disclosed the counter is provided with a disc upon which numerals are printed or otherwise suitably affixed thereto and a coil spring biased wheel or wafer having spring loaded detent pins each of which engage a stop mechanism to position the wafer and disc against movement by the coil spring. These pins are engagable by the solenoid plunger upon energization of the solenoid to disengage the detent pins from the stop to permit the coil spring to rotate the wafer and disc until the next detent engages the stop thus positioning a number to be counted or displayed corresponding to the position of the disc and detent pin.

Accordingly, it is an object of this invention to provide a high speed mechanical solenoid operated counter whose response is quicker than the mechanical counters of the prior art.

More specifically, it is an object of this invention to provide a high speed mechanical counter which is solenoid operated but which does not depend upon the solenoid to operate the counter but only to trigger the counter mechanism.

BRIEF DESCRIPTION OF THE DRAWINGS

FIG. 1 is a perspective view of the invention partly broken away and exploded to show the details thereof;

FIG. 2 is a top plane view; and

FIG. 3 is an elevational view taken along line 3—3 of FIG. 2 and looking in the direction of the arrows.

DETAILED DESCRIPTION OF THE PREFERRED EMBODIMENT

In the drawings a normally off solenoid 10 is operatively connected to the counter assembly 12 all of which are mounted on a base 14 which, in the embodiment disclosed, is one side of a container or box 16.

Solenoid 10 comprises a conventional coil 18 and a solenoid plunger 20 biased by spring 22.

Counter assembly 12 comprises a counter wheel or disc 24, which is provided with numerals on one face

thereof and rotatable with a shaft 26. These numerals are displayed in the embodiment shown, through an aperture 28 in the face plate 30 which is an end of the box 16.

To rotate the counter disc, the shaft 26 is also provided with a wafer 32 both of which are rotated by a coil spring 34 attached to the shaft at 36 and to the box at 38. The wafer 32 is also provided with a plurality of apertures 40 spaced circumferentially on the wafer coaxial of shaft 26 and in which are disposed a plurality of detent pins 42. These detent pins 42 and apertures 40 are equally spaced and correspond in number and location to the numerals on the face of the counter disc and engage a stop mechanism in the form of a fixed plate 44 juxtaposed the wafer and canted as at 46 (FIG. 2) so as to engage the pins in one direction as a stop and to cause retraction of the pins by its incline plane action when the wafer is rotated in a coil spring winding direction. As shown, the pins are spring biased in the direction of the solenoid plunger 20 by a spider type spring 48, the fingers 50 of which engage individually the heads 52 on each of the detent pins and urge them in the direction of the solenoid. The heads 52, of course, prevent the detents from moving on through the wafer.

From the foregoing, it can be seen that to operate the counter, energization of the solenoid will cause the plunger 20 to move against its bias spring 20 and engage a detent pin 42 then seated against the stop 44 causing it to move in a direction against its bias spring 48, 50 and thus be released from the stop. This will cause the coil spring 34 to rotate the wafer and concommittantly the counter disc one unit, i.e., until the subsequent or adjacent pin engages the stop mechanism since upon deenergization of the solenoid the plunger is pulled out of the way by the spring 22. If the solenoid has not been deenergized, the plunger will stop the subsequent or adjacent pin until the solenoid is deenergized whereupon the pin will move until it strikes the stop.

From the foregoing it can be seen that the solenoid 10 triggers the counter mechanism 12 and, in particular, pushes the detent pins against the springs 50 to permit the coil spring 34 to rotate the wafer in a counter-clockwise direction, during the counter assembly as in FIG. 1, with a concommittant rotation of the counter disc 24 so that the numerals 1 through 0 are brought into view of the aperture 28. In order for the counter to have a continuous operation any suitable means can be utilized to rewind the coil spring, a shaded pole-type motor being shown at 60, schematically attached to the shaft 26 through any suitable type clutching mechanism, not shown. If another type of means is used to wind the coil spring 34 this could be accomplished by simply rotating the wafer 32 and a suitable clutching mechanism, such as shown at 62, may be used so that the counter disc need not be rotated but could remain at its desired position.

What is claimed is:

1. A high speed mechanical counter comprising a solenoid having a spring biased plunger, a counter wafer rotatable on a shaft, spring means axially mounted on the shaft opposite said wafer operative to rotate said wafer and shaft, a plurality of spring biased detent means spaced radially on said wafer near the

periphery thereof and carried by said wafer so as to rotate therewith and engageable by said plunger on energization of said solenoid, the number of detent means equaling the number of counts to be counted, stop means engageable by said detent means to position said wafer by preventing operation of said spring means, said detent means being released from operation of said stop means when engaged by said plunger so as to allow rotation of said wafer and detent means, and counter disc rotatable by said wafer with numerals therein positionable by operation of said detent means, stop means and plunger.

2. The counter claimed in claim 1 wherein said spring means is a coil spring.
3. The counter claimed in claim 2 further including means to rewind said spring.
5. 4. The counter claimed in claim 1 wherein said detent means are axially movable pins axially aligned with said plunger and movable thereby.
5. The counter claimed in claim 1 wherein said counter disc is positioned with respect to an aperture to 10 be visible therethrough upon actuation of said stop means.
